UNITED STATES PATENT OFFICE.

AARON P. STORRS, OF OWEGO, NEW YORK.

DESIGN FOR A CANOPY FOR LAMP-CHIMNEYS.

SPECIFICATION forming part of Design No. 36,076, dated September 16, 1902.

Application filed January 10, 1902. Serial No. 89,237. Term of patent 7 years.

To all whom it may concern:

Be it known that I, AARON P. STORRS, a citizen of the United States, residing at Owego, in the county of Tioga and State of New York, have invented and produced a new, original, and ornamental Design for Canopies for Lamp-Chimneys, of which the following is a description, reference being had to the accompanying drawings, forming part thereof.

My invention relates to a new and original design for a canopy for lamp-chimneys.

In the drawings in question, Figure 1 is an elevation illustrating the new design; Fig. 2, a vertical section through the canopy, and Fig. 3 a plan view.

The leading or material features of the design consist of the parallel bars or ribs 1, the rings 2 and 3, between which the bars or ribs extend, and the beads 4 and 5, extending outwardly from said rings. As shown, each ring is provided with a shoulder or ledge 6, and supported upon the shoulder of the upper ring is a transparent or mica panel 7. Between the beads are arranged the serra-

tions 8. As shown in Fig. 2, each rib or bar 1 is provided with the two inwardly-curved portions 9 and the central vertical portion 10. Each bar is also shown as being fluted or serrated at 11 throughout its length, as shown. Several of the projections or teeth 8 are bent over at 12 upon the panel 7 to hold the latter in position. Near its bottom the canopy is provided with inwardly-projecting supporting-fingers 13, having vertical members 14 for sustaining the canopy in position on the chimney.

Having now described my invention, what I claim as new, and desire to secure by Letters Patent, is—

The ornamental design for a canopy for lamp-chimneys described and shown.

This specification signed and witnessed this 4th day of January, 1902.

AARON P. STORRS.
